[57] ABSTRACT

A semiconductor negative impedance converter device for compensation of insertion losses attributable to the use of high impedance devices such as semiconductor controlled rectifiers in solid state telephone switching networks. The device comprises a double collector PNP transistor and an NPN transistor which can be fabricated in a single semiconductor substrate without the need for isolation of their various regions.

NEGATIVE IMPEDANCE CONVERTER

FIELD OF THE INVENTION

This invention relates to a semiconductor negative impedance amplifier and, more specifically, to a semiconductor negative impedance converter device particularly adaptable for use in telephone switching networks.

BACKGROUND OF THE INVENTION

In many switching applications, such as in a telephone central office switching network, a transmission path is provided between given input and output lines by selectively establishing crosspoint connections in the switching network. Such a switching network typically includes a plurality of switching matrices between groups of input and output lines, each stage containing one or more switching matrices. In some switching networks, the matrices are interconnected to provide a plurality of paths between each line in the input line group and each line in the output line group, while other switching networks provide a unique path between any given line in the input line group and any given line in the output line group.

The use of solid state devices such as semiconductor controlled rectifiers for line switching applications is of increasing importance in communications systems. These devices, however, have a relatively high impedance as compared with electromechanical switches and introduce significant insertion loss in the signal path. Compensation for the high insertion losses is normally required for each line of a switching system requiring a large number of negative impedance amplifiers for each line. Therefore, the principal object of this invention is to provide a negative impedance amplifier to compensate for the high insertion losses in a solid state communications network.

A further object is to provide a negative impedance converter which can be conveniently and inexpensively fabricated on a single semiconductor substrate with a minimum number of components.

SUMMARY OF THE INVENTION

The present invention is directed to a semiconductor negative impedance converter device which may be utilized to compensate for high impedance devices used in a solid state line switching applications in communications systems. This converter is fabricated in a single semiconductor substrate without the need for isolation of its individual regions.

In accordance with the present invention there is provided a negative impedance converter module which comprises a semiconductor substrate of a first conductivity type having first, second, and third spaced regions of a second conductivity type formed therein. A fourth region of the first conductivity type is formed within the third region. First, second, third, and fourth spaced electrodes conductively contact each of the first, second, third and fourth regions, respectively. An insulating layer overlies and is in contact with the substrate in the areas between first, second, and third regions. Optionally, a fifth region of the second conductivity type may be formed in the semiconductor substrate to function as a base diffused resistor. A fifth spaced electrode conductively contacts the fifth region and may be electrically connected to the third and fourth regions by an electrically conductive overlay on the insulating layer.

A second resistive element external to the substrate is connected between the second and third electrodes. The negative impedance converter comprises various transistor elements as well as one of the resistive components which are built up from a single semiconductor substrate. The substrate contains a double collector PNP transistor, an NPN transistor and an optional resistive element. The device, therefore, performs the function of providing a negative impedance amplifier with solid state operation. The device may be fabricated using standard silicon technology requiring the same number of process steps as a simple planar NPN transistor process.

In operation a current is passed through the device from the first to the second electrode. Initially, this current flows through the resistive components of the device, the transistors being cut off. At some predetermined value of current, I_1 , the NPN transistor will begin to conduct providing base drive for the double collector PNP transistor. In the current range from 0 to I_1 , the device exhibits a positive resistance characteristic. As the applied current increases beyond the I_1 value, it is split into two paths by means of the double collector PNP transistor which has now been placed into conduction by the NPN transistor. One of the two PNP collectors is the base region of the NPN transistor thereby forming a regenerative loop. The other PNP collector is returned to the second terminal of the device.

Since one collector of the PNP is in a regenerative loop with the NPN transistor, the device will exhibit a negative incremental resistance. This means that a further increase in current results in a decrease in the terminal voltage of the device. As the amount of current increases to a second predetermined value, I_2 , the current through the first PNP collector will be sufficient to drive the NPN into saturation and the device will again exhibit a positive resistance characteristic for further increases in current. Only the current in one of the two collectors drives the NPN. The current in the other collector flows directly into the second terminal of the device. The value of current at the second predetermined value I_2 is the sum of the currents flowing through the two PNP collectors. The dynamic range and negative resistance value of the device is a function of the ratio of the two PNP collector currents. This property of the device will be made clearer in the more detailed description of the preferred embodiment to follow.

In normal operation, the device is biased with a current such that the circuit operates in the negative resistance region. While operating in this region, the device acts as a negative impedance converter. The magnitude of the negative resistance of the device is determined by the resistance components as well as the collector current ratio in the double collector PNP transistor.

The features of the present invention which are believed to be novel are set forth with particularity in the attendant claims. The invention, together with further objects and advantages thereof, may best be understood by reference to the following description taken in connection with the drawings. In the several figures, like reference numerals identify like elements.

BRIEF DESCRIPTION OF THE DRAWINGS

FIG. 1 is partially a cross sectional representation and partially a schematic representation of the device in accordance with the present invention;

3
FIG. 2 is a schematic diagram showing the device of FIG. 1; and

FIG. 3 is a graphical representation of the voltage versus current characteristics of the device shown in FIG. 1.

DESCRIPTION OF THE PREFERRED EMBODIMENT

Referring now to FIGS. 1 and 2, there is shown a module 20 in accordance with the present invention. The module is fabricated in an n-type silicon substrate 21 which has formed therein the p-type segments: 22, 23, 24, 25, 26, and 27; and regions 28 and 29. An n-type region 30 is formed within the region 28. The recited regions can be made by methods well known in the art, for example, by selective diffusion of impurities into the substrate 21. Metal electrodes 35, 36 and 37 are formed in contact with segments 22, 24 and 26 to collectively form the first collector region 40 of the PNP type transistor Q₁. These electrodes are electrically connected together and connected to a terminal point 41. Metal electrodes 42, 43 and 44 are formed in contact with segments 23, 25 and 27. These segments collectively form the emitter region 50 of the PNP transistor and are electrically connected together as well as to the input terminal 51. Another metal electrode 52 is formed in contact with region 30 and forms the emitter of the NPN type transistor 55. Further metal electrodes 56 are formed in contact with region 28 and 29 and interconnects both 28 and 29, region 29 being a base diffuse resistor. Electrode 61 contacts region 29 to form the second base resistor contact. These electrodes can be made, as is well known, by deposition of a suitable metal, such as aluminum through apertures etched in an insulating layer 58 which is formed over the substrate 21. The insulating layer 58 may be, for example, silicon dioxide, which can be conveniently grown on a silicon surface by heating in an oxygen atmosphere.

The regions 40, 50, and 28, together with substrate 21 may be considered as comprising a double collector PNP transistor Q₁. The regions 28 and 30, together with substrate 21, may be considered as comprising an NPN transistor Q₂. The region 29 as hereinbefore indicated is an optional base diffused resistive element 59. A second resistive element 60 is electrically connected between input terminal 51 and electrode 56.

The linear arrangement of the various regions in the substrate as shown in FIG. 1 is given by way of example only. Other geometrical arrangements, such as circular, known to those skilled in the art, may also be used. The number and distribution of regions used as one of the collectors in the PNP transistor and the emitter in the PNP transistor is a function of the desired design characteristics of the device which is discussed hereinafter.

As shown in FIG. 2, the input terminal 51 is connected to resistor 60 and emitter 50 of PNP transistor Q₁. Resistor 60 is connected to the base 61 of the NPN transistor Q₂ and to the second collector 62 of transistor Q₁ as well as to resistor 59. Resistor 59 is electrically connected to the output terminal 41 and emitter 44 of transistor Q₂ and the first collector 40 of Q₁. The base 65 of transistor Q₁ is in common and electrically connected to the collector 66 of transistor Q₂, represented by region 28 in FIG. 1.

When a voltage is applied to the device shown in FIGS. 1 and 2 with terminal 51 positive with respect to terminal 41, a current, I, limited by the resistors 59 and

60 will flow. If this current is increased to a value I₁, where

$$I_1 = V_{be} (NPN) / R_1 \quad (1)$$

5

the NPN transistor Q₂ will begin to conduct. The NPN collector current is the base drive for the PNP transistor Q₁ which will also start to conduct. Since the second collector 62 of Q₁ is in a regenerative loop with Q₂, the device will begin to exhibit a negative incremental resistance. This means that a further increase in current, I, results in a decrease of the terminal voltage V_{AB}. At some higher value of I, the current through the second collector 62 of transistor Q₁ will be sufficient to drive the NPN transistor Q₂ into saturation and the device will again exhibit a positive resistance characteristic. The voltage versus current characteristics of this device are graphically shown in FIG. 3 where the voltage and current in milliamperes (ma) is measured between the input and output terminals 41 and 51.

In normal operation, the device is biased with a current, I_B, such that

$$I_1 < I_B < I_2 \quad (2)$$

25

This biases the device in the negative resistance region. 30 The magnitude of the negative resistance has been derived as

$$R = R_2 [1 - \alpha_n / (1 + \alpha_{p1} \alpha_n - \alpha_{p1} - \alpha_{p2})] \quad (3)$$

35

where α_{p1} is the current gain for collector 1 of transistor Q₁, α_{p2} is the current gain for collector 2 of transistor Q₁, and α_n is the current gain for transistor Q₂. In 40 these devices α_n is the current gain for transistor Q₂. In these devices α_n is preferably very nearly unity and therefore

$$R = R_2 [1 - 1 / (1 - \alpha_{p2})] \quad (4)$$

45

The ratio of α_{p1} to α_{p2} is controlled by the device geometry; that is, the surface area of the collector region which in the lateral structure shown in FIG. 1 is the 50 length ratio of segments 22, 24, and 26 to region 28. The multiple emitter segments 23, 25 and 27 of Q₁ are interleaved with the first collector segments 23, 25, and 27 to obtain the proper interaction. This α ratio which is a critical parameter, is controlled by the mask making process which is capable of providing the necessary precision.

The boundary points defining the negative resistance region are shown in FIG. 3.

$$V_1 = [(R_1 + R_2) V_{be} (NPN)] / R_1 \quad (5)$$

55

$$I_1 = [V_{be} (NPN)] / R_1 \quad (6)$$

$$V_2 \approx 1 \text{ volt} \quad (7)$$

65

$$I_2 \approx [V_{be}(\text{npn})]/\alpha_{p2}R = I_1/\alpha_{p2}$$

(8)

An operative embodiment of the device shown in FIG. 1 has been constructed utilizing the following circuit parameters:

resistor 59—400 Ω resistor 60—700 Ω

bias current—1.9 milliamperes

bias voltage—1.4 volts

 $\alpha_{p1}/\alpha_{p2} = 9$ $\alpha_n \approx 1$

The various features and advantages of the invention are thought to be clear from the foregoing description. Various other features and advantages not specifically enumerated will undoubtedly occur to those versed in the art, as likewise will many variations and modifications of the preferred embodiment illustrated, all of which may be achieved without departing from the spirit and scope of the invention as defined by the following claims.

What is claimed is:

1. A semiconductor negative impedance converter module having only an input and an output terminal comprising:

- a semiconductor substrate of a first conductivity type;
- first, second, and third regions of a second conductivity type formed completely within such substrate, said first and second regions each having

10

15

20

30

outer dimensions defining a continuous volume of material of said second conductivity type and said regions being separated within said substrate;

- a fourth region of said first conductivity type formed within said third region, said fourth region having outer dimensions defining a continuous volume of material of said first conductivity type; and
- first, second, third and fourth spaced electrodes conductively contacting said first, second, third and fourth regions respectively.

2. A semiconductor module as defined by claim 1 which further comprises a fifth spaced region of said second conductivity type formed in said substrate and a fifth and sixth electrodes conductively contacting on opposite sides of said fifth region, said fifth region having outer dimensions defining a continuous volume of material of said second conductivity type.

3. A semiconductor module as defined by claim 1 wherein said second and third electrodes are coupled by resistive means.

4. A semiconductor module as defined by claim 2 wherein said third electrode is coupled to said fifth electrode.

5. A semiconductor module as defined by claim 1 wherein said first region comprises a plurality of distributed and spaced segments of a second conductivity type formed in said substrate, and said second region comprises a plurality of distributed and spaced second segments interleaved with said first segments.
